Primary Examiner — Mojtaba Tehrani(57) **CLAIM**

The ornamental design for controller for medical device, as shown and described.

DESCRIPTION

1. Controller for medical device
  2. Controller for medical device
  - 1.1 : Isometric [Top, Left side]
  - 1.2 : Top
  - 1.3 : Back
  - 1.4 : Front
  - 1.5 : Right
  - 1.6 : Left
  - 1.7 : Bottom
  - 1.8 : Isometric [Bottom, Right side]
  - 2.1 : Isometric [Top, Left side]
  - 2.2 : Top
  - 2.3 : Back
  - 2.4 : Front
  - 2.5 : Right
  - 2.6 : Left
  - 2.7 : Bottom
  - 2.8 : Isometric [Bottom, Right side]
- Portions shown encompassed in broken lines form no part of the claimed design; the broken lines depict unclaimed portions of the controller only and form no part of the claimed design.

1 Claim, 16 Drawing Sheets(56)
